UNITED STATES PATENT OFFICE.

MORRIS BATTER, OF NEW HAVEN, CONNECTICUT.

LAUNDRY TUB OR TRAY.

1,108,120.

Specification of Letters Patent. Patented Aug. 25, 1914.

Application filed March 24, 1913. Serial No. 756,489.

To all whom it may concern:

Be it known that I, MORRIS BATTER, a citizen of the United States, residing at No. 6 Winter street, in the city of New Haven, in 5 the county of New Haven and State of Connecticut, have invented a new and useful Laundry Tub or Tray, of which the following is a specification.

My invention relates to improvements in 10 laundry tubs or trays in general, and particularly to those made of cement and known as granite laundry tubs.

The objects of my improvement are:— First: to provide a laundry tub with means 15 for attaching a curtain to or suspending it from the upper edges of the front and sides of the tub. Second: to have these suspending means countersunk in the body of the tub, so as not to interfere with anybody or 20 anything. Third: to have these suspending means simple, durable and inexpensive. Fourth: to do away with the inconvenience of having to remove the curtain each time 25 that the tub is to be opened, when the curtain is attached to the cover of the tub, as is the current practice. I attain these objects by the device illustrated in the accompanying drawings, in which—

Figure 1 is an isometrical view of the tub 30 with my suspending means visible on the front and left side thereof, and Fig. 2 is a part section of the remote or right side of the tub by a plane A B C perpendicular to the sides of the tub.

Similar numerals refer to similar parts 35 throughout the several views, as follows:

1 is the left side, 1^a the right side, 2 the rear, 3 the middle wall or partition and 4 is the front of the laundry tub.

5, 5^a, 6 and 7 are the so called metal casings or upper rims of the four sides of the tub.

8, 8 are recesses or alcoves, shown as circular in shape but which could also have any suitable outline; 9, 9 are curtain rings or 45 links, which can be connected to the curtain by means of suitable pins or hooks not shown in the drawings; 10, 10, are sockets supporting the curtain rings.

The recesses 8, 8 and the sockets 10, 10 50 could be formed by embossing the metal of the casings, as shown in Figs. 1 and 2 or in any other suitable manner.

Fig. 2 shows the body of the tub as made of cement; but my improvement could be 55 applied to tubs made of any materials, such as slate, stone and others; the method of forming the recesses 8, 8 and the sockets 10, 10 may then be different, as above described.

Many other modifications may be made in 60 my laundry tub or tray within the scope of my invention. I, therefore, do not restrict myself to the form of my device as herein disclosed.

What I claim as my invention and desire 65 to secure by Letters Patent is:—

1. A laundry tub or tray comprising a body of cement and a metallic rim or casing, and having embossed in said casing sockets 70 adapted to support suitable curtain suspending means.

2. A laundry tub or tray comprising a body of cement and a metallic rim or casing, and having embossed in said casing sockets and alcoves, said sockets being adapted to 75 support curtain-suspending means, and said alcoves being adapted to house the said sockets.

MORRIS BATTER.
